UNITED STATES PATENT OFFICE.

OLIVER SCHLEMMER, OF CINCINNATI, OHIO.

VALVE.

973,075.

Specification of Letters Patent. Patented Oct. 18, 1910.

Application filed January 23, 1908. Serial No. 412,261.

To all whom it may concern:

Be it known that I, OLIVER SCHLEMMER, a citizen of the United States, residing at Cincinnati, in the county of Hamilton and State of Ohio, have invented certain new and useful Improvements in Valves, of which the following is a specification.

The object of my invention is to provide a valve of improved construction and operation, and my invention consists in the combination and arrangement of parts herein-after described and claimed.

In the drawings Figure 1, is a vertical section of a valve embodying my invention. Fig. 2, a section on line 2—2 of Fig. 1, Fig. 3, a section on line 3—3 of Fig. 1, Fig. 4 a section on line 4—4 of Fig. 3, Fig. 5, a bottom plan view of the valve disk shown in Fig. 1, and Fig. 6, a vertical section of another form of valve stem mounting.

In the construction illustrated in the drawings, the valve casing A has a removable valve seat B screw threaded therein. The valve seat is provided with openings or ports b at either side and a central opening for the passage of the valve stem c. On valve stem c and below seat B is secured the valve disk C which is provided with ports c' adapted to register with ports b when turned to the proper position. The connection between valve disk C and its stem c is preferably made by means of a cross pin c⁴ driven through stem c and lying between two pins c⁵. A lug c² and a permanent stop b' on valve disk C and valve seat B serve to stop the disk when in closing position. It will be seen that by providing a permanent stop at closing position of the valve, and contained within the casing, the closing position of the valve is permanently and definitely located and accidental or mischievous displacements prevented. Moreover by having the permanent stop within the valve casing the one assembling the valve may see the relative positions of the parts, thus the more readily assembling them in correct positions.

An adjustable ring a' is secured to casing A by means of set screw a² and carries a stop a³ adapted to coöperate with arm e³ to limit the opening movement of valve disk C. It will be seen that by adjusting the ring a' and stop a³, the opening movement of valve disk C may be regulated as desired, to give either a full opening to the valve or any smaller extent of opening. This will be found to be a very desirable feature, espe-

cially in hot water heating systems where the circulating head varies at different radiators, so that if radiators of the same size had the same sized valve openings those having the greater circulating head the friction being the same would receive more than their due proportion of the hot water. By adjusting the stop a³ to permit opening of the valves in accordance with their circulating heads, all radiators may be supplied with their due proportion of water, notwithstanding variations in circulating head.

At the section occupied by the valve disk and seat, the area of the passage through the casing A is considerably enlarged as shown, and the combined area of the ports in the disk or seat are made equal to or greater than the area of the inlet or outlet, which are equal in area. The disk C is provided with composition packing blocks D having beveled edges d. In the top of casing A is threaded a plug E in which the valve stem c is threaded with a comparatively steep thread h. At its lower end e, plug E is ground to fit a seat a in casing A. A stuffing box e' is threaded to the upper end of plug E. The usual couplings are provided at either opening of casing A. By this construction it will be seen that by turning stem c, the ports c' may be brought to register with ports b, and steam, water or other fluid under pressure permitted to pass upward through the valve seat and casing, as indicated by the arrows. As stem c is turned in plug E in one direction, the slight play between pins c⁴ and c⁵ will permit the valve disk to be depressed to free it from the valve seat before the disk begins to turn, thus permitting easy turning to open ports b, while when turned to the opposite direction, the disk will be first brought to closing position and then forcibly and positively pressed against the valve seat so as to tightly close the ports b. The beveled edges d of packing blocks D will serve to scrape off sediment or scale from the valve seat. By adjusting plug E, the tightness of the contact between disk C and valve seat B may be regulated as desired. When it is desired to repack the stuffing box e', plug E may be screwed down until its ground lower end e seats on valve seat a and closes the passage against leakage. Owing to the fact that the valve disk and seat are interposed between the source of supply and the stuffing for the valve stem,

the pressure on the stuffing is always relieved when the valve is closed, thus lengthening the life of the stuffing and facilitating re-packing. By making the valve seat B removable, repairs and adjustments thereof are facilitated.

In Fig. 6, I have illustrated another form of valve stem mounting, especially adapted for use with very high pressure. Here the 10 valve stem *c* is suviled in a threaded plug or support *G*, having an operating handle *g*. By this construction it will be seen that the valve disk may be turned to closing position and then tightly clamped to its 15 valve seat by turning plug *G*. When it is desired to open the valve plug *G* may be operated to force the disk from its seat, whereupon the disk may be readily turned by means of stem *g*.

20 While I have illustrated and described the preferred construction for carrying my invention into effect, this may be varied without departing from the spirit of the invention. I therefore do not wish to be limited to the exact construction set forth but 25

What I claim as new and desire to secure by Letters Patent is:

1. In a device of the class described, the 30 combination of a flat valve seat provided with a port, a rotatable disk valve having a port adapted to register with the port in the valve seat, a rotatable valve stem carrying the valve and having a connection with the valve which permits of limited rotary 35 play between the stem and valve, and means for moving the valve toward and away from its seat upon rotation of the valve stem, substantially as specified.

2. In a device of the class described, the 40 combination of a flat valve seat provided with a port, a rotatable disk valve having

a port adapted to register with the port in the valve seat, a rotatable valve stem carrying the valve and having a connection with the valve which permits of limited rotary 45 play between the stem and valve, and an adjustable plug having a threaded connection with the valve stem, substantially as specified.

3. In a device of the character described, 50 the combination of a valve casing, having an enlarged portion between its inlet and outlet, a flat valve seat provided with ports, said flat valve located in said enlarged part of casing, a valve disk having a port adapted 55 to register with the ports in the valve seat, and held against the seat by the pressure of the confined fluid, an adjustable threaded support ground at its lower end to fit a seat in the valve casing, and a valve 60 stem mounted in the threaded support and carrying the valve, as set forth.

4. In a device of the class described, the combination of casing *A*, valve seat *B* threaded therein, valve disk *C* carried by 65 valve stem *c* and having limited rotary play therein, and the adjustable threaded plug *E* having a threaded connection with valve stem *c*, substantially as specified.

5. In a device of the class described, the 70 combination of a valve seat provided with a port, a valve disk having a port adapted to register with the port in the valve seat, packing blocks having beveled edges, said beveled edges adapted to scrape the valve 75 seat, and means for turning the valve disk, substantially as specified.

OLIVER SCHLEMMER.
